WRITING GUIDE FOR THE BLIND

Filed Oct. 6, 1931

UNITED STATES PATENT OFFICE

ALICE SHARP, OF RED BLUFF, CALIFORNIA

WRITING GUIDE FOR THE BLIND

Application filed October 6, 1931. Serial No. 567,252.

This invention relates to devices for the use of the blind and pertains particularly to a device for assisting the blind in writing.

The primary object of the present invention is to provide a writing device for the blind by means of which a blind person is enabled to keep the lines of writing parallel and to maintain a straight margin along the side of the pad on which the writing is placed.

10 Another object of the invention is to provide a writing guide for the blind having means associated therewith whereby the lines of writing may be evenly spaced apart.

15 A still further object of the invention is to provide a writing guide having stencil plates associated therewith whereby a blind person will be guided in placing the heading of a letter in the proper position.

The invention will be best understood from 20 a consideration of the following detailed description taken in connection with the accompanying drawing forming part of this specification, with the understanding, however, that the invention is not confined to any strict 25 conformity with the showing of the drawing but may be changed or modified so long as such changes or modifications mark no material departure from the salient features of the invention as expressed in the appended 30 claims.

In the drawing:

Figure 1 is a view in top plan of the device embodying the present invention;

35 Figure 2 is a view in side elevation of the same;

Figure 3 is a longitudinal sectional view taken on the line 3—3 of Figure 1;

Figure 4 is a transverse sectional view taken on the line 4—4 of Figure 1;

40 Figure 5 is a plan view of a stencil plate, the same being broken centrally to show the same on a reduced scale.

45 Referring now more particularly to the drawing wherein like numerals of reference indicate corresponding parts throughout the several views, the device embodying the present invention comprises a frame which is indicated generally by the numeral 1. This frame has a relatively heavy bottom 2, the vertical side walls 3 and 4 and the head wall

5 which connects the side walls in the manner shown.

The bottom or rear end of the frame is open and the bottom 2 thereof has upon its top surface near the open rear end, the cleat 55 6 against which the lower edge of a writing pad 7 positions when it is placed in the frame and resting upon the bottom thereof, as illustrated in Figures 3 and 4.

The side wall 3 which is at the right hand 60 side of the frame when the same is in position for use, has an inturned flange 8 at its top edge which overlies the pad 7 when the same is in position in the frame. The opposite side wall 4 which is at the left of the frame 65 extends straight upwardly to a plane above the flange 8 and formed longitudinally through this straight wall is a slot 9, the lower edge of which is provided with the relatively deep notches 10. These notches 70 extend downwardly to a point in close proximity to the top surface of the frame bottom 2 as illustrated. As shown in Figure 2 the first of the notches 10 at the head of the frame is spaced a slightly greater distance from the next adjacent notch than the other notches are spaced apart. All of the notches with the exception of the head notch are 75 spaced the width of a line of writing.

Associated with the frame are stencil 80 plates, one of which is shown in position therein in Figures 1, 3 and 4 and is indicated by the numeral 11, while a second stencil plate, indicated by the numeral 12, is illustrated in Figure 5.

In association with one of the stencil plates there is used a guide and hand rest which is indicated generally by the numeral 13. This guide and rest comprises a flat plate which has a strip 14 secured across one 85 end edge, which strip is extended at one end beyond the adjacent side edge of the plate 13, forming the finger piece 15 by means of which the plate is shifted when in use.

In using the present writing device after 90 the pad 7 has been placed in position therein, if a letter is to be written, there is then placed upon the top sheet of the pad the stencil plate 11 which as shown in Figure 1 has a space 16 formed therethrough adjacent the top for 95

the date or any other heading and below this space there is formed a second space which is indicated by the numeral 17 and which extends from a point adjacent the writing side 5 of the device to a point adjacent the longitudinal center, and which is for guiding the writer in placing the salutation in the proper position. Beneath this salutation slot there is another short slot which is indicated by 10 the numeral 18 and which extends from a point adjacent the center of the device to the right side thereof, in which the first line of the letter is started. Below the first line slot 18 the stencil plate is provided with the equi- 15 distantly spaced slots 19 which extend the full width of the plate and are for the guidance of the writer in placing the additional lines of writing upon the paper. This plate 20 after being positioned on the pad then has placed thereover the line guide or regulator plate 13.

This has one side edge held in place beneath the flange 8 while the opposite side edge is maintained in position by the finger edge 25 piece 15 which extends through the slot 9. The slots 16 to 19 inclusive in the plate 11 are so disposed with respect to the notches 10 that when the line regulator plate is held in position by the engagement of the finger 30 piece 15 in one of the notches, the top edge of the guide strip 14 will lie along the lower edge of a slot. The user of the device is then able to write as desired and at the same time start the lines at the proper place and keep 35 them parallel and equidistantly spaced apart, even though it is impossible for him to see the writing.

The plate 12 is provided throughout with 40 slots 20 which are disposed therein in the same manner as the slots 19 are disposed in the plate 11 and this plate is for use in writing all the pages following the first page which is written with the first mentioned or 45 starting plate 11.

From the foregoing description it will be 50 readily seen that with a device of the character herein described a blind person may readily write a letter or other paper without getting the words or lines out of position or mixed up and at the same time the paper will 55 present when finished a neat appearance.

Having thus described the invention, what is claimed is:-

1. A writing device for the blind, comprising a paper holder, a slotted body disposed at one side of said holder, a stencil plate to be positioned over a paper sheet in the holder, and a guide member disposed in the 60 holder to extend across said stencil plate and having a portion engaged in said slot, said slot having a plurality of recesses formed along one edge to receive the said portion of the guide member.

2. A writing device for the blind comprising a pad holder having a vertical wall

extending longitudinally of one side, said wall having a longitudinally extending slot therein provided in its lower edge with spaced notches, a stencil plate adapted to be positioned in the pad holder, and a line regulator comprising a plate designed to be positioned in the holder and having a laterally extending finger disposed in said slot and adapted for selective engagement in said notches. 70

3. A writing device for the blind comprising a pad receiving receptacle having a bottom, side walls, and one end wall constituting the head of the device, one of said side walls having a longitudinally extending slot therethrough having spaced notches in its lower edge, means for maintaining a writing pad in position in the receptacle, a plate adapted to be positioned in the receptacle on a writing pad therein said plate having transverse slots therethrough, and a line regulator comprising a plate designed to be positioned in the receptacle and a lateral extension adapted to pass through said slot and be positioned in one of said notches. 75 80 85 90

4. A writing guide for the blind comprising a pad receiving receptacle having a bottom, side walls, and one end wall constituting the head of the device, one of said side walls having a longitudinally extending slot therethrough having spaced notches in its lower edge, means for maintaining a writing pad in position in the receptacle, a plate adapted to be positioned in the receptacle on a writing pad therein having transverse 95 slots therethrough, a line regulator comprising a plate designed to be positioned in the receptacle and a lateral extension adapted to pass through said slot and be positioned in one of said notches, and an inwardly extending flange formed integral with the top edge of the other longitudinal wall to overlie said plates and a paper pad in the receptacle. 100

5. A writing device for the blind, comprising a paper holder, means designed to be placed in the holder over a sheet of paper therein for assisting the writer to write in a straight line and properly space the lines one from the other, a guide overlying said means for assisting the writer in locating a writing implement on the proper line, and means facilitating the shifting of said guide over said first means in regulated steps, each step locating the guide relative to the first means for the starting of a new line. 110 115 120

6. A writing device for the blind, comprising a paper holder, means designed to be placed in the holder over a sheet of paper therein for assisting the writer to write in a straight line and properly space the lines one from the other, a guide overlying said means for assisting the writer in locating a writing implement on the proper line, a member carried by said guide, and extending laterally therefrom and means for facilitating 125 130

tating the shifting of the guide over the first
means in regulated steps, comprising a se-
ries of spaced notches formed along one lon-
5 gitudinal edge of a wall of the paper holder
in which notches said member may be selec-
tively engaged.

In testimony whereof I hereunto affix my
signature.
